UNITED STATES PATENT OFFICE.

WALTER A. BOCKIUS, OF PARK RIDGE, ILLINOIS.

ELECTRICAL CONDENSER.

Application filed February 13, 1925. Serial No. 8,889.

The invention relates to electrical condensers and more particularly to the type generally known as "straight-line" condensers.

In this type, when used in radio systems, it is desirable to provide for variation of the maximum capacity of the condenser and also to provide a construction in which the condenser, under maximum varying capacities, utilizes a full stroke of the movable plates so as to give a substantially full scale and proportionate reflection on the indicator, notwithstanding the variation in the maximum capacity.

This object is accomplished primarily by providing for the adjustment of one set of interleaved plates, so that the maximum capacity may be varied, and in such a manner that, under variable maximum capacities, the capacity will be graduated down from the maximum during a full stroke of adjustment in the movable set.

The invention consists in the several novel features hereinafter set forth and more particularly defined by claims at the conclusion hereof.

In the drawings: Fig. 1 is a plan of a condenser embodying the invention, the supporting wall being shown in section. Fig. 2 is a section taken on line 2-2 of Fig. 1. Fig. 3 is a section taken on line 3-3 of Fig. 1. Fig. 4 is a perspective of the slideway in which the movable set of leaves is supported.

The invention is exemplified in a condenser comprising a set of rectangular plates 4 which are rigidly secured together by means of washers 5 to which the plates are soldered to form a unitary structure. A rod 6 extends through these plates and washers and constitutes a support therefor. Rod 6 is provided with a head 8 which is confined in a channel 9 formed in a guide-plate 10 which is secured by screws 11 to a supplementary supporting plate 12. The rod 6 passes through a slot 13 to the back of guide-plate 10 and the foremost washer secured to leaves 4 is provided with lugs 14 which fit against the sides of slot 13 to hold the set of leaves 4 against rotation. The set of plates 4 is held on rod 6 by a thumb-nut 15 and the rod is also secured in its assigned position in the guide-plate 10 and against vertical movement by the nut which clamps the leaves 4 and washers 5 against the back face of guide-plate 10. A rotatable set of plates 16 are secured to washers 17. This plate and washer

structure is rotatably held on a stationary shaft 18 by a nut 19, it being understood that these leaves and washers are free to rotate when held on said shaft. The plates 16 are interleaved with plates 4 and each plate 16 comprises a short arm 16^a and has one of its edges 16^b generally radial and an outer edge or periphery 20 which is approximately circumferential. The relative shapes of plates 16 and 4 are such as to cause an approximately straight line variation in capacity by rotation of the leaves 16 into and out of interleaved relation with plates 4. A dial 21 is provided with a thumb-wheel 22, which is fixed to a shaft 23 which extends through the board or support 24 and also through the auxiliary supporting plate 12. A pinion 25, fixed to shaft 23, meshes with a segment 26 fixed to rotate with plates 16 and washers 17. This thumb-wheel and dial are thus adapted to rotate the leaves 16 to bring the interleaved plates in greater or lesser lapped relation to correspondingly vary the condensing efficiency. Stops or pins 27 are secured in plate 12 to limit the rotative movement of segment 26 so that the plates 16 will be stopped at a position where the capacity of the condenser is a maximum or minimum.

By vertically adjusting shaft 6 and plates 4 relatively to the fulcrum of plates 16, the maximum lapped relation of the interleaved plates may be varied to provide the varying maximum capacities of the condenser. While plates 4 are in different vertical adjustments, the plates 16 may have, at all times, a full range of movement and a characteristic of the invention is that a full stroke of the plates 16, under varying maximum capacities of the condenser, will result in a variation which will be reflected on the dial 21 throughout a substantially full stroke. As a result, the maximum capacity may be varied and the dial reflection will be proportionate to the movement of the plate 16 during substantially the full stroke of the dial.

The invention exemplifies a "straight-line" condenser which provides for a variation in the maximum capacity of the condenser and in which the rotatable adjustment of one set of plates relatively to the other reflects a substantially proportionate variation on the dial under different maximum capacities. The device is simple in construction and provides for ready adjustment of the maximum capacity whenever desired.

Both sets of leaves and operating mechanism for the rotatable set are mounted in a supplementary plate which may be easily applied to the usual supporting board of a

5 radio set.

The invention is not to be understood as restricted to the details set forth, since these may be modified within the scope of the appended claims, without departing from the

10 spirit and scope of the invention.

Having thus described the invention, what I claim as new and desire to secure by Letters Patent, is:

1. In an electrical condenser, the combination of a pair of sets of interleaved plates,

15 one of which is stationary and the other freely movable into and out of lapped relation with the stationary set, and means for adjusting one set in a substantially recti-

20 linear path relatively to the other set to increase or decrease the maximum capacity of the condenser and so as to effect proportionate variation by operating the freely movable set.

25 2. In an electrical condenser, the combination of a pair of sets of interleaved plates, one of which is stationary and the other freely rotatable into and out of lapped relation with the stationary set, and a slidable

30 connection for adjusting the stationary set in a substantially rectilinear path relatively to the rotatable set, so as to increase or decrease the maximum capacity of the condenser and to effect proportionate variation by the rotation of the rotatable set.

35 3. In an electrical condenser, the combination of a pair of sets of interleaved plates, one of which is stationary and the other freely movable into and out of lapped relation with the stationary set, and means for

40 bodily adjusting one set relatively to the other set to increase or decrease the maximum capacity of the condenser and so as to effect proportionate variation by operating the freely movable set, comprising means for clamping the bodily adjustable set in its assigned position.

45 4. In an electrical condenser, the combination of a pair of sets of interleaved plates, one of which is stationary and the other freely rotatable into and out of lapped relation with the stationary set, and means to

50 bodily adjust the stationary set relatively to the rotatable set, to increase or decrease the maximum capacity of the condenser so

55 as to effect proportionate variation by the

rotation of the rotatable set, comprising a rod and means for conjointly clamping the rod and the adjustable set in assigned positions.

60

5. In an electrical condenser, the combination of a pair of sets of interleaved plates, one of which is stationary and the other rotatable, an auxiliary supporting plate adapted for attachment to a support, means for mounting the rotatable set on said plate, and means for adjustably mounting the stationary set on said plate to bodily adjust it relatively to the rotatable set to increase or decrease the maximum capacity of the condenser.

70

6. In an electrical condenser, the combination of a pair of sets of interleaved plates, one of which is stationary and the other rotatable, an auxiliary supporting plate adapted for attachment to a support, means for mounting the rotatable set on said plate, means for adjustably mounting the stationary set on said plate to bodily adjust it relatively to the rotatable set to increase or decrease the maximum capacity of the condenser, and means for operating the rotatable set carried by the auxiliary supporting plate.

75

7. In an electrical condenser, the combination of a pair of sets of interleaved plates, one of which is stationary and the other rotatable, an auxiliary supporting plate adapted for attachment to a support, means for mounting the rotatable set on said plate, a slidable connection for supporting the stationary set on said plate so it may be bodily adjusted in a substantially rectilinear path relatively to the rotatable set to increase or decrease the maximum capacity of the condenser, and means for operating the rotatable set carried by the auxiliary supporting plate.

80

8. In an electrical condenser, the combination of a pair of sets of interleaved plates, one of which is stationary and the other of which is freely rotatable into and out of lapped relation with the stationary set, and means for bodily moving one of the sets relatively to the other to increase or decrease the distance between the stationary set and the axis of the rotary set so as to vary the maximum capacity of the condenser.
